REVERSING VALVE MECHANISM FOR
POWER-OPERATED VACUUM PUMPSEugene S. Mariotte, Syracuse, N. Y., assignor to
Lipe-Rollway Corporation, Syracuse, N. Y., a
corporation of New York

Application March 27, 1946, Serial No. 657,492

2 Claims. (Cl. 230—52)

1

This invention relates to reversing valves for reciprocating motors, and has for its object a valve mechanism which operates or reverses with a snap action, and is particularly adapted for use in vacuum pumps, which embody a double acting piston motor for actuating a double acting pump piston, in which the amount of vacuum controls the operation of the power motor, stopping it when the vacuum reaches a predetermined value greater than the pressure of motive fluid or air which actuates the power motor, and permitting the power motor to start when vacuum is reduced and the pressure in the power cylinder is greater than the retarding effect of the vacuum, which mechanism in addition to giving a quick opening and closing of the ports through which the motive fluid flows to and exhausts from the motor, also prevents stopping of the valve in an intermediate or dead center position upon stopping of the motor, so that the motor will always start and continue running when the force of the vacuum is less than the pressure of the motive fluid in the power cylinder. As is known, the pressure in the power motor is controlled through a pressure regulating valve set to pass to the power motor, air at a predetermined maximum pressure. This valve mechanism is particularly designed for creating vacuum to withdraw the push piston or plunger in a stock bar feed for automatic metal working machines, where the push piston is under power pressure in a cylinder to feed the bar and is withdrawn by vacuum when the bar is used up or too short, to permit a new bar to be inserted in the cylinder in front of the plunger. For example, see Mariotte Patent No. 2,327,916 granted August 24, 1943.

The invention consists in the novel features and in the combinations and constructions hereinafter set forth and claimed.

In describing this invention, reference is had to the accompanying drawings in which like characters designate corresponding parts in all the views.

Figure 1 is a plan view of a vacuum pump equipped with this reversing valve mechanism.

Figure 2 is a longitudinal sectional view taken centrally of Figure 1.

Figures 3 and 4 are transverse sectional views taken on the planes of lines 3—3 and 4—4, respectively, of Figure 1.

Figure 5 is an enlarged exploded isometric view of a reversing valve.

Figures 6 and 7 are transverse views showing the position of the movable valve member at different points in the operation of the valve.

This valve mechanism for double acting cylin-

der and piston motors includes, generally, a driving rocking element connected to a reciprocating part of the motor, as the piston rod, to be rocked thereby when the motor is in operation, a second or driven rocking element actuated by the first through a lost motion in either direction, a valve member shiftable by the second rocking element to be reversed in either direction thereby, and means energized by the first rocking element to actuate the second rocking element in either direction, after the lost motion between the two elements is taken up. The valve mechanism is here shown as embodied in a vacuum pump unit.

1 designates the cylinder, and 2 the piston of a reciprocating motor carried by a frame 3 of any suitable construction. 4 designates a pump cylinder also carried by the frame 3 having a double acting piston 6 working therein, the cylinder 4 being carried by the frame 3 in axial alinement with, but axially spaced from, the power cylinder 1. The pistons 2 and 6 have a piston rod 7 in common. 8 designates the valve mechanism as a whole, this being mounted on the frame 3 between the opposing ends of the cylinders 1 and 4 and includes a suitable casing or body 9 mountable on the main body 3 between the cylinders and being here shown as a separable unit from the body 3. The casing is formed with a valve chamber 10.

11 and 12 are parts of driving and driven rocking elements mounted, and here shown as coaxially arranged, on the casing 9, the first element 11 including a rock arm 11A rotatably mounted concentric with the second element 12 which includes a spindle or shaft 12A rotatably mounted in a bore or bushing 110 located in the bore in the casing 9 coaxial with the valve chamber 10. The spindle or shaft 12A extends into the valve chamber 10 and has a valve member or head 13 thereon which rocks therewith, the head 13 co-acting with a stationary valve member or disk 14 in the bottom of the chamber and being virtually part of the frame 3.

15 designates an arm which is a component part of the first rocking element. It is mounted to rock idly about the bushing or sleeve 110. 16 designates a pair of spaced apart rock arms mounted on the outer end of the spindle 12A to rock therewith. It constitutes a part of the driven rocking element 12. Spaced apart stops 50 or lugs 17 are provided on the rocking arm 11A between which the arm 15 extends, the lugs being spaced apart a greater distance than the width of the arm 15. The pair of rocking arms 16 are also arranged in the path of movement of the arm 15 and are spaced apart a greater distance than

the width of the arm 15, so that there is a lost motion connection between the arm 15 and the arms 16 in either direction of the rocking movement. When the driving rocking element 11 or the arm 11A is rocked from the piston rod 7, one or the other of the arms 17 transmits the motion thereof to the arm 15 in one direction, the arms 16 remaining stationary. As the arm 15 approaches one of the arms 16, taking up the lost motion between them, an actuator is energized which re-acts on the arm 15 after it has been moved by the arm 11A a predetermined distance and encounters one of said arms 16 under the reaction and operates the driven rocking element and the valve head with a snap action. During the snap action, the arm 15 moves out of engagement with the lug with which it was engaged, into engagement with the other lug. The means for timing this snap action includes inclined cam or plane surfaces 18 provided on the arm 15 or the hub thereof, these surfaces being wedge faces which meet at an apex or point 19. The actuator is a spring-pressed follower 20 movable in a suitable guide 21 carried by the casing 9. The follower is preferably provided with a roller or anti-friction member 22 which coacts directly with the cam surface 18. The rocking element is actuated from the piston rod 7, and as here shown, the arm 11A at the end thereof extends over the piston rod 7 and is provided with spaced apart pins 23 which form a fork arranged astride a collar, as 24, on the piston rod 7. As the piston rod shifts axially in either direction, one of the lugs or stops 17 moves the arm 15 idly, and in so doing moves one or the other of the cam surfaces 18 (in accordance with the direction of the rocking movement) along the roller 22 and follower 20, thus moving the follower against the action of its spring. The driven element 12 remains stationary. However, as the arm 15 moves toward one of the arms 16 of the driven element, the apex 19 of the cam passes over the roller from one side to the other thereof, so that the spring of the follower 20 re-acts and the follower or its roller presses against the cam surface 18 on the other side of the apex, and hence crosses the driving rock arm 15 which in the meantime has moved up toward the rock arm 16 with a snap action. Hence, the valve 13 is reversed with a snap action. During this snap action, the arm 15 takes up the lost motion between the stops 17 and hence reverses so as to be in position relatively to the arm 11A to be driven in the reverse direction, when the valve reverses.

The valve members themselves may be of any suitable construction. As here shown, the stationary valve member 14 is provided with an air intake port 26 and ports 27 and 28, which are connected by bores or passages 29 and 30 to ports at opposite ends of the power cylinder 1. The stationary member 14 is also formed with exhaust ports 32, 33 which open into exhaust passage 34 to the outer air common to both. The movable or rockable valve member 13 is formed with transfer passages 35 and 36 in its face opposed to the face of the stationary valve member 14. The intake port 26 is connected to an intake bore 31 for connection to a source of supply of compressed air, by a suitable pipe having a suitable On and Off valve therein.

In Figures 2 and 6, the piston 2 is shown as at the end of its power stroke to the right and the valve has reversed to let the power pass through the right end of the cylinder 1 and exhaust from the left end of the cylinder 1, so that the air will

pass from the inlet port 26 into the transfer passage 35 out through port 27, passage 29 into the cylinder 1 at the right end thereof to actuate the piston 2 to the left end. At the same time the left hand end of the cylinder is opened to exhaust through the passage 30, port 28, transfer passage 36 of the movable valve member 13 out through exhaust port 33 to exhaust passage 34. When in this position, exhaust passage 32 is closed. 5 During the movement of the piston to the left, the rocking element 11 is rocked carrying the rock arm 15 to the left or clockwise in Figure 5, until it picks up the left hand rock arm 16 on the spindle 12, and during this movement, cam surfaces 18 have moved so that one of them loads the spring for the follower 20, and further so that the point of the apex 19 of the cam becomes centered with the follower 20 or the roller 22 thereof, whereupon the spring of the follower 10 re-acts to move down the other cam surface 18 and rock the driven element 12 with a delayed snap action to reverse the valve member 13. Upon this reversal of the valve member 13, it takes the position shown in Figure 7, wherein the left hand 15 end of the cylinder 1 is open to the intake of air and in the right hand end of the cylinder 1 is open to exhaust through the passage 29 and exhaust port 32, exhaust port 33 being then closed. 20 The arm 11A which coacts with the piston rod 30 7 is virtually a driving member, and the member 15, a motion transmitting arm actuated by the member 11A through one or the other of spaced lugs 17 to transmit the motion to the driven element, which is the element 12 including the shaft 35 12A, through the arms 16. The spring-pressed plunger 20 constitutes means coacting with the oppositely inclined cam faces 18 on the motion transmitting arm 15 which terminate in an apex or point at 19, to actuate the motion transmitting arm 15 with a delayed snap action, and hence 40 actuate the arm 16, shaft 12A and the valve head 13, with a snap action, when the driving element 11 or the components 11A and 15 thereof have been actuated to shift the arm 15 from one arm 45 16 toward the other, so that the follower 21 is on the point or apex 19 of the cam, and hence works the motion transmitting member 15 with a snap action, and hence actuate the valve head 13 with a snap action. This means, therefore, always 50 locates the valve head 13 under stalled conditions where the motor will start against and not remain stalled or in dead center, when the predetermined air pressure in the power cylinder predominates over the vacuum in the pump cylinder 55 or in the tank in which the vacuum is created. By reason of this valve, the vacuum automatically controls the operation of the power cylinder to automatically start and work when the vacuum falls below a predetermined value and stop when 60 the vacuum is at a predetermined value. 65 The vacuum pump or the cylinder thereof is provided with a check valve 38 at each end thereof for permitting the escape of air when the vacuum is on the other side of the piston, and also with a check valve 39 at each end opening inwardly and both connected to the tank chamber or other device from which the air is being evacuated by the piston. While the piston 6 is moving to the right end of the cylinder 1 70 into the position shown in Figure 1, the air on the right hand piston is free to exhaust through the right hand check valve 38 while suction is being produced on the left hand side of the piston 6 through the valve 39. During the movement of the piston 6 to the left, the air on the 75

left side of the piston exhausts through the left hand valve 38 while suction is being produced on the right hand side of the piston 6 through the right hand check valve 39.

This pump is a particularly simple, compact unit and the valve mechanism a particularly compact unit in itself and combined with the cylinder and piston arrangement of the motor and the pump.

What I claim is:

1. A reversing valve mechanism for double acting cylinder and piston motors for controlling the flow of motive fluid to and from opposite sides of the piston of the motor, the valve mechanism including a body having a valve chamber therein, a driving rock arm having means for connection to a part actuated by the piston of the motor to be actuated thereby, a driven shaft mounted in the valve casing and extending into the valve chamber, a valve member mounted on the shaft in the chamber, the driving rock arm being mounted to rotate about the axis of the shaft relatively thereto, a motion transmitting rock arm mounted coaxial with the shaft to rock relatively thereto and a pair of rock arms mounted on the shaft and extending on opposite sides of the former rock arm and spaced apart a distance greater than the width of the former rock arm, stops on the driving arm between which the motion transmitting rock arm extends, the motion transmitting rock arm having inclined cam surfaces which meet and form an apex, and a spring-pressed follower coacting with the cam surfaces and arranged to act on one or the other of the cam surfaces to shift the motion transmitting rock arm with a snap action when the apex of the cam passes over the follower.

2. A reversing valve mechanism for vacuum pumps which include a double acting cylinder and piston motor and a double acting reciprocating pump actuated by the piston of the power motor, the valve mechanism controlling the flow

of motive fluid to and from opposite ends of the cylinder of the motor; said valve mechanism including driving and driven reversely movable elements, and a motion transmitting member between them, and means controlled by the motion transmitting member to actuate the driven element only when the driven element is approaching the end of its movement in either direction, to actuate said motion transmitting member relative to the driving and driven elements to reverse the valve mechanism with a snap action after the motor and valve mechanism have been stalled by the vacuum in the pump cylinder overcoming the pressure of the motive fluid in the power cylinder and the vacuum decreases where it is less than the pressure of the motive fluid on the power piston, said motion transmitting member being arranged to move as a unit with the driving element in either direction and also relatively thereto and being provided with oppositely inclined cam faces meeting at an apex, and said means including a spring-pressed follower movable along one of the other of the cam faces during the movement of said motion transmitting member by the driving member in either direction and operating to shift with a snap action when the follower rides on the apex of the cam.

EUGENE S. MARIOTTE.
